UNITED STATES PATENT OFFICE.

CHARLES D. SMITH, OF NEW YORK, N. Y.

FEED-WATER HEATER AND STEAM-GENERATOR.

SPECIFICATION forming part of Letters Patent No. 225,537, dated March 16, 1880.

Application filed August 9, 1879.

To all whom it may concern:

Be it known that I, CHARLES D. SMITH, of New York, in the county of New York and State of New York, have invented certain new and useful Improvements in Feed-Water Heater and Steam-Generator, of which the following is a specification.

This invention relates to that class of devices for water and steam heaters and circulators in which the bridge-wall itself forms a portion of such water and steam circulator, and connects, by means of a series of steam coils and pipes, with the water and steam spaces of the boilers, and also with the service or feed pipe.

Its object is to produce a more thorough and vigorous circulation of water in the boilers to heat the feed-water before its introduction into said boilers, and also to act as an auxiliary steam-generator from the large amount of heating-surface which it affords; and to this end it consists, first, in a vertical pipe-coil within the walls of a furnace upon one or both sides of a boiler, running the full length or any desired length of such boiler, partly above and partly below the grate-bars of the furnace, such horizontal steam-coil being constructed of pipes and return-bends, or bent pipe and couplings of any approved style, and having its respective ends connected with the water and steam spaces of the boiler to insure a good circulation of water through said coil and to carry the steam generated therein to the boiler; second, in a vertical manifold set bottom upward within the walls of a furnace, so as to extend above and below the grate-bars, communicating by means of suitable connections with the steam and water spaces of a boiler, and provided with a blow-off cock or exit outside of said furnace-wall to clear its pipes when fouled; third, in two or more vertical manifolds arranged so as to extend above and below the grate-bars and within the furnace-walls, situated between two boilers, with the steam and water spaces of which each manifold communicates by means of suitable connections, and having between them a suitable box filled with non-conducting material, or a plate, for the purpose of shutting off the heat and preventing its transmission to the adjacent manifold and boiler and resultant waste when only one of the two boil-

ers is used; fourth, in a vertical steam and water coil running from below the grate-bars and above the water-line of a boiler, provided with connections for the purpose of carrying away the steam to the boiler and bringing the feed-water from the drum or bridge-wall into the coil, the coil being connected with the drum or bridge-wall, induction feed-water pipe, and with the steam-space and water-space of the boiler; fifth, in a horizontal coil located between the bridge-wall or drum and rear wall of a furnace beneath the boilers, and connected with the drum and with the water-spaces and the steam-spaces of the boilers, and provided with suitable branch pipes at proper intervals in the coil for carrying steam to the boilers; sixth, in a series of brick columns or a brick wall capped by an iron plate running from the bridge-wall back to the rear end of a boiler for the purpose of supporting a horizontal steam-coil connecting with a bridge-wall and a boiler or boilers.

In the accompanying drawings, Figure 1 represents a detached view, in perspective, of one of the boilers with a portion of the furnace-walls and also of the boiler broken away, and also showing its various connections. Fig. 2 is a view, in perspective, of one of the boilers with a portion of its walls broken away, and also showing its various connections. Fig. 3 is a view, in perspective, of one of the boilers with a portion of its wall removed, and also showing its various connections. Fig. 4 is a plan view of all the boilers, a portion of their walls being broken away to show the parts beneath, showing the boilers and their connections *in situ*. Fig. 5 is a cross-section of the furnace, taken from behind the drum, showing the boilers *in situ*.

Similar letters indicate similar parts of the invention.

The brick walls of the furnace are represented at A, while A' indicates the furnace-doors, behind which are the grates upon which the fuel is consumed beneath the boilers. The doors of the ash-pits beneath the grates are shown at A'', while the grates themselves are shown at a.

A series of steam-boilers are shown at B, B', and B'', which are set in the furnace-walls in the usual manner.

At C is shown a combined drum and bridge-

100

wall passing transversely across the furnace from side to side and through the walls of the same, through which the steam and feed-water pass, and below which the inner ends of 5 the grate-bars *a* are supported in any suitable manner.

From the combined drum and bridge-wall *C* springs a branch pipe, as shown at *C'*, with return-bends, and terminating in pipe *C''*, 10 which passes through the rear wall of the furnace, rises upward, and enters the boiler *B'* at the boiler-head above the water-line. The pipe *C''* is furnished at its lower end with a blow-off cock.

15 From one of the bends or elbows of branch pipe *C'* rises a steam-pipe, *c'*, which passes through the side wall of the furnace, rises upward, and enters boiler *B* above the steam-space, thus conveying steam from the said 20 branch pipes at intervals to the boilers.

At *c''* is shown an auxiliary pipe, which sprouts from the drum or bridge-wall *C*, and conveys steam from it to the boiler *B'*.

D represents a stack or coil of steam-pipes 25 arranged horizontally between the boiler *B* and the side of the furnace-wall. This coil commences with an elbow, *d*, rising above boiler *B* and communicating with its steam-space, and consists of a series of horizontal 30 pipes connected by return-bends. The first of these horizontal pipes extends from the vertical portion of the pipe *d³*, which enters the boiler from a point at about the middle of the side wall of the furnace, to return-bend 35 near the front wall of the furnace. The next four of these horizontal steam-pipes extend the whole length of the side furnace-wall, the lower or fourth one resting upon the drum *C*, while the two lowest pipes of the coil are 40 short ones, extending horizontally between the drum *C* and the front wall of the furnace. The lower pipe of the coil runs below the level of the grates *a*, while the lowest pipe of all 45 passes through the front wall of the furnace, turns upward by means of the elbow shown at *d⁴*, and enters the water-space of the boiler *B* through the boiler-head by means of the double elbow shown at *d''*.

E, Fig. 2, represents a manifold set bottom 50 upward, so that its columns *e* stand with their ends, caps, or plugs downward below the grate-bars *a*, and connected to a lower horizontal pipe, *e'*, by means of nipples or tees tapped in or connected with it by any suitable device. 55 This lower pipe, *e'*, passes through the front or side wall of the furnace and ends in the blow-off cock 2, for the purpose of cleaning the pipes of the manifold when they are fouled. This manifold *E* is set between the boilers *B* and *B'*, its lower pipe resting upon the floor 60 of the furnace, while its upper horizontal pipe, *e''*, connects at one end with the steam-space of the boiler *B'*. The other end passes out over the front wall of the furnace, and by means 65 of two elbows enters the water-space of the boiler *B'* through its front boiler-head.

At *F* are shown two manifolds or sets of

steam-pipes connected together at the bottom by means of the horizontal pipes shown at *f*, 70 into which the columns are fitted, and which rest near the furnace-floor. The lower horizontal pipes shown at *f* pass through the front wall of the furnace *A*, and rising vertically upward enter the water-spaces of boilers *B'* and *B''* by means of elbows through their 75 respective boiler-heads, while the extremity of the lower pipe, *f*, projecting outward through the front wall of the furnace, is adapted to be connected with a suitable supply-pipe for conveying water to the columns of the manifolds *F*. 80

The upright columns of the manifolds *F* end in the elbows *f'*, of much smaller diameter, which connect with the horizontal upper pipes, *f''*, the outer ends of which are closed, while their inner ends enter the steam-spaces of 85 boilers *B'* and *B''* by means of elbows. These manifolds *F* are set between the boilers *B'* and *B''*, having a space between them, and stand above the floor of the furnace, between its front wall and the drum *C*. 90

In the space between the manifolds *F* is shown a box, *G*, made of plates of metal riveted together, and it is designed to be filled with any suitable non-conducting material. This box is for the purpose of cutting off the radiation of heat between boilers *B'* and *B''* when it is not deemed expedient to use the latter. Where there is not room for the box *G* a single plate of iron or a brick wall may be used as a cut-off. 95

At *H*, Fig. 3, is shown a vertical steam-coil composed of the parallel pipes connected by return-bends *h*. From the tops of these return-bends spring the small elbows *h'*, which bend over the boiler *B''* and open into the horizontal pipe *h''*, which communicates with the steam-space of the boiler by means of an elbow. The rear end of the steam-coil *H* enters the drum *C*, while its outer end passes through the front wall of the furnace and enters the water-space of the boiler *B''* through the boiler-head. 100

At *I* is shown a steam-pipe, which passes upward from the last bend of the horizontal branch coil *C'* and enters the steam-space of 115 boiler *B''*.

I do not limit myself to the use of two or three boilers; but any number may be used in connection and combination with my devices.

It may be deemed necessary in some instances to support the horizontal branch steam-coil *C'* by means of a series of brick columns or a brick wall capped with iron and running back from the drum or bridge-wall *C* to the rear furnace-wall. 120

The lower bends of the vertical coil *H* may be tapped and have a pipe or series of pipes from each bend to blow out the dirt and sediment that may accumulate and settle in the bottom of the coil. 125

What I claim is—

1. A vertical steam-coil within the walls of a furnace, upon one or both sides of a boiler, partly above and partly below the grate-bars 130

of the furnace, such vertical steam-coil being constructed of pipes and return-bends or bent pipe and couplings of any approved style, and having its respective ends connected with the water and steam spaces of the boiler to insure a good circulation of water through said coil and to carry the steam generated therein to the boiler, all constructed and arranged substantially as set forth and described.

5 2. A vertical manifold set bottom upward within the walls of a furnace, so as to extend above and below the grate-bars, communicating, by means of suitable connections, with the steam and water spaces of a boiler, and provided with a blow-off cock or exit outside of said furnace-walls to clear its pipes when fouled, all constructed and arranged substantially as set forth and described.

10 3. Two or more vertical manifolds having pipes arranged so as to extend along the boiler above the water-line and below the grate-bars and within the furnace-walls, situated between two boilers, with the steam and water spaces of which each manifold communicates, and

15 having between them a suitable box filled with non-conducting material, or a non-conducting plate or wall, for the purpose of shutting off the heat and preventing its transmission to the adjacent manifold and boiler when

20 only one of the two boilers is used, substantially as set forth and described.

25 4. The combination of a vertical steam and water coil provided with connections for the purpose of carrying away the steam to the

boiler and bringing the feed-water from the 35 drum or bridge-wall into the coil, which is connected with the bridge-wall induction feed-water pipe, all constructed and arranged substantially as shown and described.

5. A horizontal coil located between the 40 bridge-wall or drum and rear wall of a furnace, and communicating with said drum and with a blow-off cock, in combination with the boilers, to which it is connected by suitable pipes, substantially as and for the purposes 45 specified.

6. In combination with the boilers and their connections, a series of brick columns or a brick wall capped by iron plate running from the bridge-wall back to the rear end of a boiler 50 for the purpose of supporting a horizontal steam-coil connecting with the bridge-wall and a boiler or boilers, substantially as set forth and described.

7. In combination with the series of boilers, 55 a pipe, C'', and coil C', leading from the drum C upward to one of the boilers, and connected therewith above the steam-space of the same, all constructed and arranged substantially as and for the purposes specified.

In testimony that I claim the foregoing I have hereunto set my hand in the presence of the subscribing witnesses.

CHARLES D. SMITH.
